poration of New Jersey

Filed Mar. 13, 1963, Ser. No. 73,959

Term of patent 14 years

(Cl. D74—5)

FIG. 1

FIG. 2

FIG. 3

FIG. 4

FIGURE 1 is a top plan view of a combined calendar and desk set, showing my new design;

FIGURE 2 is a front elevational view thereof;

FIGURE 3 is a side elevational view thereof; and

FIGURE 4 is a rear elevational view thereof.

The characteristic features of my design reside in the combined calendar and desk set disclosed, wherein the desk set and the calendar are mounted on a rectangular plate which in turn is mounted on a larger rectangular base having an upper surface that is downwardly inclined from the front and rear to a longitudinal groove that lies forward of the longitudinal center line of the base, all as shown.

I claim:

The ornamental design for a combined calendar and desk set, as shown and described.
